BUCKS FOR PRESSING MACHINES

Ira C. Maxwell, Ole H. Langen, and Peter W. Tongen, Minneapolis, Minn., assignors to The Unipress Company, Incorporated, Minneapolis, Minn., a corporation of Minnesota

Application May 15, 1953, Serial No. 355,232

12 Claims. (Cl. 223—73)

This invention relates to new and useful improvements in bucks for pressing machines and more particularly to new and useful improvements in bucks for power driven sleeve presses of the one lay type disclosed in our co-pending application, Improved Pressing Machine, Ser. No. 307,456, of which this application is a division of the subject matter contained therein.

In the utilization of power driven pressing machines adapted for high productivity per unit of time, there has long remained the problem of providing sufficient heat to all surfaces of the buck for drying the moisture out of the garment and also the buck padding. This has been particularly true in bucks of the type which are utilized for pressing tubular garment sections, such as shirt sleeves, pant legs, etc. The specific problem of providing sufficient heat to all surfaces of the buck for drying the sleeve moisture out of the garment and also out of the buck has not been solved. This has resulted in a slowing down of production and has limited the utilization of pressing machines of this type in that only a certain number of tubular sections per hour could be pressed as there was not enough heat transferred to all surfaces of the buck in order to evaporate the moisture of the garment which has been driven into the buck padding by the action of heated presser heads.

The problem has arisen by virtue of the fact that the heated presser heads close on both sides of the buck, in fact, substantially enclose the buck and evaporate the moisture in the garment section which is driven back into the padding of the buck. Furthermore, steam is sometimes supplied directly from the presser heads which tends to supplement this moisture. The buck padding must therefore be kept hot enough so that this steam does not condense as moisture and when the heads open up there must be enough heat behind the buck padding so that the water will evaporate.

Furthermore, when the buck is of the vertical type as shown in our co-pending application, Ser. No. 307,456, and when tubular garment sections are sleeved thereon, the buck is usually constructed of a U-shaped structure having an expanding wing therein. A pipe is provided on the inside of this structure which is heated by steam and which radiates heat to the metal. However, the very U-shaped construction of this buck provides a chimney effect and there has remained the problem that there is insufficient radiation from any heating means to the metal form of the buck and consequently the buck will not dry out the buck padding, thus limiting the shirts which may be ironed per unit of time. This is highly advantageous in that the time limitations of the machine itself are much less than the limitations of the buck. Consequently, if novel and efficient means are provided for heating the buck and evaporating the moisture, the number of garments per unit of time may be materially increased.

It is therefore an object of this invention to provide an improved form upon which a tubular garment section may be sleeved for pressing;

2

It is a further object of this invention to provide an improved buck for a one lay sleeve press;

5 It is still another object of this invention to provide an improved buck heating circuit for supplying heat to the buck which will enable rapid elimination of moisture from the garments during the pressing operation and quick drying of the buck padding;

10 It is a further object of this invention to provide in a pressing machine having a vertical buck and pressing heads adapted to substantially enclose the same, an improved form of buck upon which tubular garment sections may be sleeved for pressing operation;

15 It is a further object of this invention to provide an improved buck having highly efficient thermal communication with the heating means therefor;

20 It is a further object of this invention to provide a buck having heating means therein;

25 It is still a further object of this invention to provide a new and improved buck with rapid drying characteristics so that the number of garments pressed per unit time is materially increased;

30 It is a further object of this invention to provide an improved buck heating mechanism comprising a portion of the buck form;

35 It is still a further object of this invention to provide a buck and heating means therefor for efficiently transferring heat to all metal surface areas of the buck;

40 Further objects of this invention rely in the improved heating means for the buck, in the method of connecting the heat containing conduit to the buck heating surfaces and the inner tube and novel steam delivery provisions;

45 Other and further objects of this invention are those inherent and apparent in the apparatus as illustrated, described and claimed.

50 The invention will be described with reference to the drawings in which corresponding numerals refer to the same parts and in which:

Figure 1 is a side elevational view, partly in section, of the instant invention showing the buck in use in connection with the pressing machine of the type described in our co-pending application Ser. No. 307,456.

Figure 2 is a horizontal sectional view taken along the lines and in the direction of the arrows 2—2 of Figure 1;

Figure 3 is a horizontal sectional view taken along the lines and in the direction of the arrows 3—3 of Figure 1;

Figure 4 is a side elevational view of the buck of Figure 1 with the padding and other parts removed and showing the connection of the buck plates to the heat supply pipe;

Figure 5 is a horizontal sectional view taken along the lines and in the direction of the arrows 5—5 of Figure 4;

Figure 6 is a view similar to Figure 5 but taken along the lines and in the direction of the arrows 6—6 of Figure 4;

Figure 7 is likewise a view similar to Figures 5 and 6 but taken along the lines and in the direction of the arrows 7—7 of Figure 4;

Figure 8 is an exploded view similar to Figure 6 and showing the buck plates exploded from the heat supply pipe;

Figure 9 is an enlarged vertical sectional view of the buck heating pipe;

Figure 10 is an enlarged horizontal view through the buck structure. It is similar to Figure 2 but shows the buck cover loosened at one side and partly folded back, and the next layer of buck padding on the same side also partially folded back, illustrating the layers of cover, padding, etc. of the buck;

Figure 11 is a fragmentary elevational view, somewhat enlarged, and it shows in detail the upper buck cover

holder, by means of which the buck cover is held taut; and

Figure 12 is a view of the key by means of which the buck cover holder of Figure 11 may be manipulated as during installing and replacing the buck cover.

Referring now to Figure 1, the buck generally designated 10 is supported by base casting 11 on its support plate 12 by cap screws 13. Plate 12 is in turn supported by angle members 14 attached to a mounting plate 15 which is secured to the frame of a pressing machine in any conventional manner.

The pressing machine, with which this buck is used, forms no part of this invention per se and consequently will not be described in detail. An exemplary form of pressing machine with which this buck may be used is disclosed in our co-pending application, Ser. No. 307,456, as aforesaid.

The base casting 11 of the spatulate buck 10 has a flange at 16 and is hollow inside except for an angularly disposed web 17 which connects the side walls. It is to this base casting 11 that the plates 18 of the spatulate form are attached by pins 19 passed through apertured washers 19A. Referring to Figure 6, it is seen that these plates 18 are generally flat but are curved toward each other at the front edges 18A. The rear edges 18B of these plates are welded into longitudinal grooves at 18C which are milled in a heavy walled steel tube 20. The attachment of the edges 18B to the steel tube 20 may be by welding, copper brazing or other suitable fastening means, the only essential being that the fastening be mechanically strong and capable of ready transmission of heat from the tube 20 to the plates 18.

The plates 18 are attached to the base casting by means of pins 19, and are separated by washers 19A. Plates 18 serve as supports for the tube or pipe 20. The pipe 20 is plugged at its upper end by plug 21 and has its lower end adjacent the lower edge of the plates 18 bent at 22 so as to extend down through the hollow base casting 11, through the hole back of web 17 therein. The pipe 20 is again bent at 23 so as to extend down between the flanges 14 as at 24 of Figure 1 so as to allow steam and condensate water connections to be made thereto.

Referring to Figure 9, it will be noted that pipe 20 extends down to a Y-connection at 25. To one branch of the Y-connection is screwed the nipple 26 which has attached to it a smaller diameter tube 28, preferably of copper, which extends all the way up the pipe 20 and terminates adjacent the plug 21 at the upper end of the pipe 20. To the nipple 26, there is attached a coupling 29, which is in turn attached to a steam connection pipe, not shown. To the other branch of the Y-connection 25 there is attached a nipple 30 which is connected to a suitable condensate water return, not shown. The introduction of the steam at the top of the pipe 20 adjacent the plug 21 insures that a full steam supply is made to the entire interior surface of the pipe 20 and the condensate is returned quickly and efficiently out of the pipe. It was found by lengthy experiments that the heating of the pipe 20 with high pressure steam provides adequate heat for the elimination of water from the buck pads even at high rates of ironing production and with damp shirts, it was found also that by having the plates 18 welded or otherwise firmly connected to the pipe 20, that the heat is conducted adequately throughout the area of the plates 18 and hence given off on the surface of the buck pad 31, thereby aiding in the elimination of moisture. The open construction of the base casting 11 and the spacing of the tube plates 18 of the spatulate buck, which are likewise open at their upper ends, produce a certain chimney effect which maintains the interior of the buck free from condensation.

The buck plates 18 are widest at their base and taper to a narrower dimension at their upper ends, so as to conform generally to the shape of shirt sleeves, pant legs, or other tubular garment forms. The upper ends

of the plates 18 are attached together by a top casting 32 which is held in place by screws 33. The construction of one type of top casting is described in our co-pending application, Ser. No. 145,258, now Patent No. 2,687,241. The top casting may be of any desired type as to facilitate the sleeving of a tubular form onto the spatulate buck, and forms no part of this application per se.

While this invention has been described with reference to a vertically positioned buck for use with tubular garment sections, it is to be understood that it may likewise be used with reference to a horizontally positioned buck for tubular garment sections or to horizontally or vertically positioned bucks for use with other garment sections.

Referring to Figure 8, it will be noted that by milling the groove 18C to approximately the thickness of the plate 18 a smooth outer surface is produced at the junction of the plates 18 and the tube 20, plates 18 being easily ground off and polished, if desired. Upon the smooth exterior surface thus formed by the two plates 18—18 and the tube 20, there is mounted a suitable buck padding of one or more layers 31 and 34. The layer 31 is preferably made of cloth knitted from rust resistant wire, such as Monel metal, or the like, the pad being composed of a plurality of plies of such fabric. Upon such resistant woven metallic pad 31 is preferably laid a pad 34 comprised of one or more layers of flannel and over this there is tightly stretched the exterior buck cover 35. Experience has shown that for the average surface encountered in presses of this type, that the buck cover 35 should best be made with very tough fabric, such as nylon fabric.

The attachment of the nylon cover 35 is accomplished in the following way: The nylon cover has its opposite edges sewed so as to form headings 38 and 39 in which there are placed thin, flat, comparatively narrow steel rods 40 and 41. At the upper and lower ends of the space between the steel side plates 18 there are provided brackets 42 which have holes 43 longitudinally therethrough which serve as sliding supports for rods 44. At the rear ends of the rods 44, there are washers 45 held in place by the cotter pins 46. To the front ends of each of the rods 44, there is attached a T-shaped head 48 having a hole 49 therein. The spring 50 is pressed between the bracket 42 and the washer 45 and tends to draw the rod 44 back in the direction of the arrow 51, as shown best in Figure 10. The T-shaped heads 48 have a thickness such that when they are turned so that the head lies parallel with the plate 18 the shoulders 52 and 53 will be disengaged from the ends of rods 40 and 41. In order to place the buck cover on the buck padding, the fabric 35 is pulled as tautly as possible by hand over the buck padding and the two rods 40 and 41 are then tucked back into the open space between the front edges 18A of the plate 18, thus confining the front edges of the padding.

In Figure 12, there is shown a hook or key which has a long shank 54, a turned over end 55 and a handle 56. The shank 54 is inserted into the space between the front edges of the buck padding and the plates 18 until the hook end 55 can be engaged in the hole 49 of the T-shaped head 48. The head is then drawn forward until it clears the rods 40 and 41 and is then turned so that the shoulders 52 and 53 engage grooves in the ends of rods 40 and 41, respectively. Then the T-shaped head 48 is permitted to be retracted under the influence of spring 50 and this throws a tensioning pressure on the rods 40 and 41, which accordingly draw the nylon fabric 35 closely and tautly over the buck padding.

It will be noted, from Figure 10, that over the front edges 18A of each of the buck plates, there is a small member generally designated 58 which has a flange 59 also to embrace the front curved-in tip 18A of the plate 18. The member 58 is a light stainless metal and is curved to fit the front bend 18A of the plate 18. How-

ever, the curved portion is provided with outwardly punched points at 60 into which the springy knitted metallic buck padding 31 is hooked in the manner that a fabric is hooked on the points of a curtain stretcher. In this way, the metallic knitted padding 31 is held from sliding back away from the edge 18A and it frictionally supports the final padding 34.

In the hollow space between the plates 18—18 of the spatulate buck, there is usually mounted a wing assembly generally designated 61. This wing is of thin sheet metal and is lightly padded and covered with nylon fabric that is dressed over its edge 62 and extends back toward its rear edge 63. At about midheight along the rear edge of said wing 61 there is a rearwardly extending lug 64 having a downwardly opening slot 65 therein, by means of which the wing may be hooked and hence pivotally suspended upon the pivot 66. Wing 61 is carried by a bell-crank lever designated 68 and has an upper crank arm 69 and a lower crank arm 70. Bell-crank lever 68 is pivoted at the pivot 71 for arcuate movement. This bell-crank lever arm 69 which extends upwardly between the plates 18 and the spatulate buck structure, has spaced members and carries pivot 66 upon which the slotted lug 64 is hung. The lever arm 69 extends down between the plates 18—18 and is bent so as to operate within the front opening in the base casing 11 and then extends downwardly to the pivot 71 whence it extends forwardly at the portion 70. This forward portion 70 of the bell-crank has a pivot at 75A and further out there is a pivot 75.

An adjustable operator actuatable rod 76 is likewise pivoted at 71 and functions as indicated in our aforesaid co-pending divisional application. Since such adjustment rod and the wing structure form no part of this invention per se, they will not be described in greater detail. The pivotal mounting of the bell-crank lever arm 68 upon pivot 71 and the provision of pivot 75A allows attachment to pivot 75 of a link not shown which may be operated to propel the buck-wing outwardly (leftwardly with reference to Figure 3). The provision of operator actuatable rod 76 likewise allows this to be done selectively at the operator's discretion.

It will be noted from Figure 1 that the upper end of the buck is narrower than the lower end and that the upper end is cut "square" whereas the lower end of the buck, corresponding in the illustration of the shoulder seam of a shirt sleeve is at an angle. Thus, referring to Figure 1, the buck, generally designated 10, has a smaller front to back dimension at its upper end than at its lower end and the padding is at substantially right angles to the longitudinal axis of the buck at the upper end 10A but is shaped at the angle along the lower end 10B. It will be understood, however, that the shape of the buck may be varied to accommodate the pressing of different shapes of garment elements.

As many widely differing embodiments of this invention may be made without departing from the spirit and scope thereof, it is to be understood that we do not specifically limit ourselves to the embodiments disclosed herein.

What we claim is:

1. A spatulate buck frame comprising a metal tube, a pair of metal plates, each plate being tangentially attached along one edge thereof in spaced parallel relation to said tube for forming a buck support, the other edge of each plate being free and steam supply and condensate water return means connected to said tube for the heating thereof.

2. A spatulate buck frame comprising a metal tube, a pair of metal plates, each plate being tangentially attached along one edge thereof in spaced parallel relation to said tube for forming a buck support, the other edge of each plate being free and steam supply and condensate water return means connected to said tube, and said tube is

provided with two longitudinal opposed recesses into which the plates are positioned and each recess having a depth substantially equal to the thickness of one of said plates.

5. The apparatus of claim 1 further characterized in that a buck pad and buck cover are drawn around the tube and said plates, the edges of said pad and covering being attached to and held to the free spaced edges of the overlying plates.

10. 3. The apparatus of claim 1 further characterized in that a metal fastener is attached to the edge of each of said plates, said fasteners having an edge portion attached to the plate and a flange overlying the portion of the plate adjacent the free edge, said flange having outwardly pertused points upon which the buck pad is snagged for support thereon.

15. 4. The apparatus of claim 3 is further characterized in that a metal fastener is attached to the edge of each of said plates, said fasteners having an edge portion attached to the plate and a flange overlying the portion of the plate adjacent the free edge, said flange having outwardly pertused points upon which the buck pad is snagged for support thereon.

20. 5. A spatulate buck frame comprising a hollow metal tube, a pair of metal plates having opposite edges, said plates being attached parallel to each other and in substantially spaced, parallel overlying relation, each plate being tangentially attached along one edge to said tube for forming a buck support the other edge of each plate being free and a hollow concentric tube located within said hollow metal tube and extending substantially the length thereof.

25. 6. A spatulate buck frame comprising a metal tube, a pair of metal plates having opposite edges, said plates being attached parallel to each other and in substantially spaced, parallel overlying relation, each plate being tangentially attached along one edge to said tube for forming a buck support, the other edge of each plate being free and steam supply, condensate water return means connected to said tube, and said tube having recessed portions into which the attached edges of said plates are seated to form a substantially smooth uninterrupted surface.

30. 7. The apparatus of claim 6 further characterized in that a buck pad and buck cover are drawn around the tube and said plates, the edges of said pad and covering being attached to and held to the free spaced edges of the overlying plates.

35. 8. A spatulate buck comprising a pair of plates of substantially the same shape having spaced edges, said plates being positioned in spaced overlying relation, said plates having adjacent free edges curved toward each other, a pipe positioned along the opposite edges of said plates, said plates being mechanically attached to said pipe in heat conducting relationship, a buck pad forming an outer covering around said pipe and plates, means for fastening the pad to the curved edges of the plates, and a buck cover of flexible material having a stiffening rod attached thereto along opposite edges, said cover being pulled around said pad and inturned into the space between the plates with the rods positioned in said space and spring tension means adjacent the ends of each plate for engaging the ends of said rods for holding them tightly therein to tension said cover.

40. 9. A spatulate buck comprising a pair of plates of substantially the same shape having spaced edges, said plates being positioned in spaced overlying relation, said plates having adjacent free edges curved toward each other, a closure means positioned along the opposite edges of said plates, said plates being mechanically attached to said closure means in spaced relationship, a buck pad forming an outer covering around said pipe and closure means, means for fastening the pad to the curved edges of the plates, and a buck cover of flexible material having a stiffening rod attached thereto along opposite edges, said cover being pulled around said pad and inturned into the space between the plates with the rods positioned in said space and spring tension means adjacent the ends of each plate for engaging the ends of said rods for holding them tightly therein to tension said cover.

45. 10. A spatulate buck comprising a pair of plates of substantially the same shape having spaced edges, said

plates being positioned in spaced overlying relation, said plates having adjacent free edges curved toward each other, a closure means positioned along the opposite edges of said plates, said plates being mechanically attached to said closure means in spaced relationship, a buck pad forming an outer covering around said plates and closure means, means for fastening the pad to the curved edges of the plates, and a buck cover of flexible material having a stiffening rod attached thereto along opposite edges, said cover being pulled around said pad and inturned into the space between the plates with the rods positioned in said space, spring tension means adjacent the ends of each plate for engaging the ends of said rods for holding them tightly therein to tension said cover, and means whereby said spring tension means are rotatable from a rod engaging position to a position in which said rod ends are disengaged.

11. A spatulate buck comprising a pair of plates of substantially the same shape having spaced edges, said plates being positioned in spaced overlying relation, said plates having adjacent free edges curved toward each other, a closure means positioned along the opposite edge of the said plates comprising a hollow metal tube, said

plates being mechanically attached to said closure means in spaced relationship.

12. A spatulate buck comprising a pair of plates of substantially the same shape having spaced edges, said plates being positioned in spaced overlying relation, said plates having adjacent free edges curved toward each other, a closure means positioned along the opposite edges of said plates, said plates being mechanically attached to said closure means in spaced relationship, means for fastening a buck pad around said plates and closure means and the curved edges of the plates including spring tension means adjacent the ends of each plate for engaging the ends of a pair of stiffening rods for supporting a buck pad thereon, and means whereby said spring tension means are rotatable from a rod engaging position to a position in which said rod ends are disengaged.
